UNITED STATES PATENT OFFICE.

SARAH P. SPENCER, JR., OF ELIZABETH, NEW JERSEY.

DESIGN FOR A BOOK-MARK.

SPECIFICATION forming part of Design No. 19,072, dated April 30, 1889.

Application filed March 19, 1889. Serial No. 303,936. Term of patent 7 years.

To all whom it may concern:

Be it known that I, SARAH P. SPENCER, Jr., a citizen of the United States, residing at Elizabeth, in the county of Union and State 5 of New Jersey, have invented and produced a new and original Design for Book-Marks, of which the following is a specification, reference being had to the accompanying drawings, forming part thereof.

10 Figure 1 is a plan of my newly-designed book-mark, and Fig. 2 an edge view of the same.

15 The leading feature of my design consists in having that portion which is visible when the marker is applied to clasp the leaves of a book shaped to resemble suggestively and approximately, though not with strict accuracy, a quill writing-pen.

20 In the drawings, A represents such pen-like portion, and B the other portion or flap, which, when the mark is applied to a book, is mainly concealed by the leaves of the book because of lying behind them, these parts forming the clasp for the leaves. The outer or feathery end of the representation of a quill pen is somewhat 25 fanciful, its extremity c being a semblance of a feathery end, and the adjacent portions d e, between such end and the body of the pen, representing two swell curves of varying sizes. The whole surface may be ornamented in any 30 color or colors and embellished to give it a finished appearance. I border the whole by a line, 8, as shown.

I claim —

The design for a book-mark, as herein described and shown, consisting of the part A, 35 having mainly the form or semblance of a quill pen, and of the broader back flap, B, and having a border-line extending all around both these parts.
